UNITED STATES PATENT OFFICE.

FREDERICK SCHIRMER, OF CLEVELAND, OHIO.

ROD-FASTENING CLIP.

Application filed July 3, 1924. Serial No. 724,172.

The present invention relates to a clip which is well adapted for use in building construction for securing pencil rods to metal joists, although it will be understood that it can be used wherever a fastening is needed for securing a rod to an intersecting supporting member.

Among the objects of the invention is to provide a fastening clip of this character which is extremely inexpensive in its construction, which can be applied with great rapidity, which provides a firm support for the rod, and which also provides for the rod being readily detached from the support when this is desired.

In building construction metal lath is ordinarily secured to so-called pencil rods which are attached to the bottom portions of metal joists. Various means have been heretofore utilized for securing the pencil rods to the joists and this is usually done by means of a strip of sheet metal which has one end thereof attached to the joist, the other end of the strip being adapted to be coiled around the pencil rod. The winding or coiling of the metal strips around the pencil rods consumes a considerable amount of time and causes the workman to make rather slow progress on the job. The fastening clips of the present invention are admirably adapted for use in securing these pencil rods to the metal joists and the clips can be applied with such rapidity that the workman can put up the pencil rods in much less time than would be required to twist the usual metal strips around the pencil rods.

One particular embodiment of the invention has been shown and described for illustrative purposes, although it will be understood that many modifications and changes can be made in the details of construction without departing from the spirit of the invention.

For a full understanding of the invention reference is to be had to the following description and accompanying drawings, in which—

Figure 1 is a side elevation of a portion of a metal joist having a pencil rod attached thereto by means of a clip constructed in accordance with the invention, the clip being shown by dotted lines in the position assumed when the hooked end thereof is flexed preparatory to placing it in engage-

ment with the joist or disengaging it therefrom.

Figure 2 is a transverse sectional view through the metal joist, showing the manner in which the hooked portions of the clip engage the upper edges of the joist flanges.

Figure 3 is a detached view of the clip.

Corresponding and like parts are referred to in the following description and indicated on all of the views of the drawing by like reference characters.

For illustrative purposes the clip is shown as utilized for securing a pencil rod to a metal joist, the pencil rod being designated by the reference character A and the metal joist being designated by the reference character B. The joist is of the usual construction, being substantially in the form of an I-beam and having flanges b at the marginal portions of the top and bottom thereof.

The clip constitutes in effect a stirrup hanger for supporting the pencil rod from the metal joist and holding it in a firm engagement with the bottom thereof. As shown on the drawing the clip is adapted to be formed of a single length of spring wire and includes a hanger arm 1 having a hooked end 2 which is adapted to fit around the upper edge of one of the flanges b of the joist. The hanger 1 is of a sufficient length to extend slightly below the bottom of the joist and a resilient arm 3 projects laterally from the lower end thereof, being connected thereto by a bight portion 4, which forms a seat to receive the pencil rod A. The free end of the resilient arm 3 is angularly deflected at 3a and terminates in an upwardly projecting hook element 5 which is adapted to engage the upper edge of the joist flange b at a distance from the hanger arm 1.

The angular bend in the resilient arm causes the body portion 3 thereof to assume a position at an acute angle to the hanger arm 1, so that the bight portion 4 of the clip will effectively engage the pencil rod A and hold it at the lower end of the hanger arm 1, thereby causing most of the load upon the pencil rod to be supported directly by the hanger arm. The bight portion 4 of the clip extends downwardly below the bottom of the metal joist a sufficient distance to receive the pencil rod A, and after the pencil rod has been placed in position the resilient arm 3

obtains a bearing thereon virtually constituting a fulcrum so that it is necessary to flex the same upwardly in order to spring the hook element 5 over the flange *b* and bring it into engagement with the upper edge thereof. The inherent resiliency of the clip then acts to clamp the pencil rod against the bottom of the metal post and hold it in a firm engagement therewith. On Figure 1 the position of the clip when it is flexed on the rod *A* as a fulcrum for bringing it into or out of engagement with the flange of the post, is shown by dotted lines.

It will be obvious that fastening clips which are constructed in this manner can be applied with great rapidity for the reason that there are no strips to be twisted or other special and time-consuming operations to be performed. A workman can thus complete the work of fastening the pencil rods to the metal posts in a very short period of time. For ordinary work it has been found that these clips can be advantageously formed from No. 14 gauge spring wire, although it will be obvious that a heavier or a lighter wire may be used if it is thought desirable to do so.

Having thus described my invention what I claim as new and desire to secure by Letters Patent is,

1. As a new article of manufacture, a joist clip comprising a body portion having a hanger arm at one end thereof and a hook element at its other end, said body portion being bent intermediate its ends to provide a resilient bearing portion in the plane of the arm and hook element.

2. As a new article of manufacture, a joist clip for connecting pencil rods to joists composed of a single piece of resilient wire, said wire being bent upwardly at one end to form a hanger arm, and at its other end to form a hook, said wire being also bent upwardly intermediate its length substantially in the

plane of the arm to form a rod receiving seat 45 adjacent to the arm and a tensioning spring connecting the hook and arm.

3. In combination, a metal joist having a vertical flange portion, a pencil rod transverse to the joist beneath the said flange, and 50 a clip connecting the joist and rod, said clip embodying a hanger arm having a hook engaging over said flange, a resilient arm projecting laterally from the hanger arm and cooperating therewith to provide a bight portion adapted to receive the rod and fulcrum thereon, said resilient arm being formed with a bend whereby the body portion thereof is disposed at an acute angle to the hanger arm, and a hook at the free end of the resilient 55 arm which is adapted to engage the flange, whereupon the resilient arm is flexed and the resiliency thereof utilized for clamping the rod against the joist, the hanger arm and lateral arm being disposed in a plane parallel to that of the vertical flange.

4. In combination, a metal joist formed with a longitudinally extending flange portion, a pencil rod extending under the joist transversely thereof, and a clip for connecting the pencil rod with the joist, said clip embodying a resilient arm forming its middle portion and disposed beneath the pencil rod, and hook elements extending laterally from opposite ends of the resilient arm 75 and adapted to engage over the edge of the flange, the resilient arm and shank portions of the hook elements being arranged in a plane parallel to that of the flange and the rod being held in the bight between the resilient arm and one of the hook elements 80 whereby when the other hook element is engaged with the flange the arm will be flexed and the pencil rod held against the joist by the resiliency thereof.

In testimony whereof I affix my signature.

FREDERICK SCHIRMER.
